Attorney

UNITED STATES PATENT OFFICE.

WILLIAM C. VEHSE, OF APPONAUG, RHODE ISLAND.

COLLAPSIBLE TUBE.

Application filed October 8, 1920. Serial No. 415,631.

To all whom it may concern:

Be it known that I, WILLIAM C. VEHSE, a citizen of the United States, residing at Apponaug, in the county of Kent and State of Rhode Island, have invented certain new and useful Improvements in Collapsible Tubes, of which the following is a specification.

This invention relates to closures for the 10 discharge end of collapsible tubes which are designed to carry tooth-paste, paint, liquid glue and other materials in paste or powder form; and the object of this invention is to provide a simple and effective valve or 15 closure device for controlling the discharge opening in the neck of the tube, the same being permanently connected to the tube to effectually prevent the annoyance which is often caused by the loss of the closure when 20 in the form of a removable cap, or the like.

The nature and advantages of the invention will be better understood when the following detail description is taken in connection with the accompanying drawings, 25 the invention residing in the combination and arrangement of parts as claimed.

In the drawings forming part of this specification, like numerals of reference indicate similar parts in the several views 30 and wherein:

Figure 1 is a perspective view illustrating my improved collapsible tube as being compressed at its end and discharging the contents upon a tooth brush.

Figure 2 is an enlarged sectional elevation showing a portion of the tube with the valve in open or discharge position.

Figure 3 is the same as Figure 2 but showing the valve in closed position.

Figure 4 is an outside elevation of my improved tube, showing the discharge opening in the neck and the operating handle on the valve, the neck portion of the tube being partially broken away to illustrate 45 the action of this handle portion of the plug to hold the plug in position after having been inserted into the neck of the tube.

Figure 5 is a top view of my improved tube.

With reference to the drawings, 10 designates the body portion of a collapsible tube which is preferably made of a soft ductile metal, the same being usually formed by an extruding process, the stock in the top 55 portion or head 11 of the tube may be left

slightly thicker than that of the body portion if desired.

The side wall of this neck portion is provided with a discharge opening 13 and the outer end 14 of the neck is preferably left open for the passage of the handle portion of the valve.

The valve or closure member 15 is preferably of the plug type being correspondingly tapered to fit the inner wall of the neck 65 portion and this plug is provided with an outwardly-extending operating end 16 which is first formed of a shape to be readily passed through the open end, and after being positioned in this neck this extending member is swaged preferably into disc shape, that portion of the disc which is connected to the plug portion of the valve being of a shape to engage the outer edge 70 14 of the neck portion to prevent the plug 75 from falling inwardly before the tube is filled, from its seat. This disc-shaped end also serves as a convenient means by which to rotate the valve.

This plug-shaped valve is provided with 80 an opening 18 through its side wall, which is adapted to register with the opening 13 in the side wall of the neck portion when the valve is turned to the desired position, which opening 18 connects with the interior 85 of the collapsible tube so that when the body of the tube is compressed the contents can be forced out through a channel or opening 18 in the plug and through the opening 13 in the neck or when it is desired to close 90 this opening 13 it is only necessary to rotate the plug so that its opening will be out of register with that of the neck.

It will be noted by this construction that the pressure on the contents of the tube, necessary for forcing the same out through the discharge opening also serves to force the plug-shaped valve against its seat rendering it tight against leaking when under pressure.

In practice these tubes are first formed into the desired shape leaving their bottom ends, or those ends opposite the discharge neck open. The next operation is to insert a valve from the inside outward and then 105 by swaging the projecting portion 16 into the shape illustrated in Figure 4, this valve is locked in position against being removed from the neck. The contents of the tube is subsequently inserted into the open end 110

thereof, which end is then sealed and the tube ready for use.

The device is extremely simple, inexpensive and practical in construction and by its 5 use the contents of the collapsible tube are retained therein and the discharge of the contents of the tube may be nicely controlled and that without removing any of the parts, which often become mislaid and 10 lost as is the case when removable caps are employed.

The foregoing description is directed solely towards the construction illustrated, but I desire it to be understood that I reserve the privilege of resorting to all the 15 mechanical changes to which the device is susceptible, the invention being defined and limited only by the terms of the appended claims.

20 I claim:

1. A collapsible tube having an internally and outwardly tapering neck portion open at its end and having a discharge opening in its side wall, a correspondingly tapered 25 plug valve seated in said neck and having an inclined discharge passageway adapted to communicate with said discharge open-

ing, and a knob-like handle on said valve projecting through said end opening.

2. A collapsible tube having a discharge 30 neck tapered on its inside and having an open outer end and also having an opening through its side wall, a corresponding tapered plug rotatably seated in said neck and having an opening to register with the opening in said neck, the outer end of said plug extending through the outer end of the neck and being flattened to form a finger-grasp, whereby the plug may be rotated in the neck. 40

3. A collapsible tube having a discharge neck tapered on its inside and having an open outer end and also having an opening through its side wall, a corresponding tapered plug rotatably seated in said neck 45 and having an opening to register with the opening in said neck, the outer end of said plug extending through the outer end of said neck and being formed to provide a finger-grasp integral with the plug and 50 larger than the opening in the outer end of said neck.

In testimony whereof I affix my signature.
WILLIAM C. VEHSE.
